(57) **CLAIM**

We claim the ornamental design for a pump control component, as shown and described.

DESCRIPTION

FIG. 1 is an elevated perspective view of the pump control component of the present claimed invention;

FIG. 2 is a front view of the pump control component shown in FIG. 1;

FIG. 3 is a side view of the pump control component shown in FIG. 1;

FIG. 4 is an end view of the pump control component shown in FIG. 1;

FIG. 5 is an opposite end view of the pump control component shown in FIG. 1; and,

FIG. 6 is a second side view of the pump control component shown in FIG. 1.

Features shown in broken lines in the drawings are not part of the claim. The bottom view is not claimed.
